Patented June 22, 1920.

FIG. 1.

FIG. 2.

FIG. 3.

Inventor
Karl Eckert
By *Henry Orthofer* Atty.

UNITED STATES PATENT OFFICE.

KARL ECKERT, OF FÄLLANDEN, SWITZERLAND, ASSIGNOR TO HANS KOCH, OF DIETIKON, SWITZERLAND.

BELT-HOLDER FOR LOOMS.

1,344,177.

Specification of Letters Patent. Patented June 22, 1920.

Application filed June 25, 1919. Serial No. 306,755.

To all whom it may concern:

Be it known that I, KARL ECKERT, a citizen of the Republic of Switzerland, residing at Fällanden, Switzerland, have invented 5 certain new and useful Improvements in Belt-Holders for Looms; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 My invention relates to belt fasteners for the belt or strap of the picker stick of looms.

It is well known that such belts are subject to variations in length, due to atmospheric conditions, and that a full shuttle requires a stronger impulse than one that is nearly empty. Long shuttles also require a greater impulse than shorter ones. By reason of this the belt or strap of the picker 25 stick must be adjusted to suit conditions and these adjustments are often made within small measurements of a millimeter or so.

My invention has for its object a device 30 on the picker stick for attaching the belt or strap to any adjusted length, so that the belt or strap can be easily and rapidly unfastened and fastened, for adjustment to prevailing conditions.

In the drawings, in which like parts are 35 similarly designated—

Figure 1 is an elevation, partly in section.

Fig. 2 is a plan view thereof, and

Fig. 3 is an elevation of a modification.

The device comprises a wedge-shaped casing 1 of rather heavy sheet metal, whose interior is also wedge shaped. The interior surface of the bottom of the casing is roughened, as indicated at 7. The sides of the casing at right angles to the bottom are bent 40 over at the top toward each other with their edges spaced apart, thus forming a slot. A bolt and nut 2 secures the holder to the picker stick 3.

Coöoperating with the casing 1 is a wedge 45 6 having smooth faces and also having a portion 5 projecting above its upper face forming a handle that is free to pass between the bent over edges of the casing 1, as clearly seen in Fig. 2.

By striking the nose or smaller end of the 55 wedge 6 or the projecting handle 5 at said end with a hammer the wedge is easily loosened and can be removed from the casing 1, whereupon the belt or strap 4 is lifted from the roughened face 7 and re-adjusted 60 with reference to the picker stick. After adjustment of the strap or belt 4 the wedge 6 is re-inserted in the casing 1 and struck on its opposite larger end to force it into the casing and to force the under surface of 65 the belt into engagement with the roughened surface 7.

In the modification illustrated in Fig. 3 the wedge-shaped casing 1 is formed as a 70 complete loop, and the wedge 6 in this instance, necessarily has the handle 5 omitted. The casing 1 is immovably connected to the picker stick 3 by the bolt, as illustrated in the drawing.

I claim:

1. A belt or strap fastener for looms, comprising a wedge-shaped casing having sides whose upper ends are bent over toward each other, and a wedge for insertion in said casing and having a portion projecting through 80 the slot formed between said bent over edges.

2. In a belt or strap holder for looms, the combination with the picker stick; of a wedge-shaped casing whose bottom is interiorly roughened for engagement with a 85 belt, means for securing said casing to a picker stick, said casing having sides whose upper edges are bent over toward each other, and a wedge coöperating with the wedge-shaped casing and having a handle projecting through the slot formed between the 90 bent over edges.

3. In a belt or strap fastener for looms the combination with the picker stick; of a wedge-shaped casing interiorly roughened 95 on its bottom, a bolt passing through said bottom and securing the casing to the picker stick, the sides of said casing having their upper edges bent over toward each other to form a slot between them, a wedge having 100 smooth surfaces, and a longitudinal central projection from its upper face forming a handle, said handle projecting through the slot formed between said bent over edges.

In testimony that I claim the foregoing 105 as my invention I have signed my name.

KARL ECKERT.
